UNITED STATES PATENT OFFICE.

JOHN A. BODKIN, OF NEW YORK, N. Y., ASSIGNOR OF ONE-HALF TO WELLINGTON B. LEE, OF BALDWIN, NEW YORK.

RAIL ANCHOR.

Application filed July 27, 1921. Serial No. 487,841.

To all whom it may concern:

Be it known that I, JOHN A. BODKIN, a citizen of the United States, and a resident of the borough of Manhattan, in the city, 5 county, and State of New York, have invented certain new and useful Improvements in Rail Anchors, of which the following is a specification.

My invention relates to an improved rail 10 anchor designed for the purpose of preventing creeping of railroad rails.

As well known, rails are held to the ties of the track by spikes which are driven into the ties with their heads overlapping the 15 edge of the rail flange, the rails, of course, being spliced to each other at intervals. Difficulty is experienced with such a construction with "creeping" of the rails which tends to force the ties out of place.

20 It is well known that all rails creep more or less, and on double track roads where the traffic on one set of rails is continuously in one direction the creepage is more pronounced. The effect of creeping is manifested in numerous ways, as by bunched or 25 slewed joint ties, locked switches, deranged crossings, and so forth. While creeping at the point of origin is almost imperceptible, yet as the creeping builds up the tracks will 30 be deranged eventually at some point. The point of origin is where the train takes on speed and if the first rail is successfully held against creep it is an easy matter to prevent creeping of the other rails.

35 It is an object of my invention to provide a simple and inexpensive means for overcoming creeping by rigidly connecting a number of ties together, particularly at the rail joints, which enables me to obtain substantially maximum ballast resistance.

40 In general, my invention comprises a device so shaped as to be capable of being driven into two or more ties to rigidly secure the ties to each other, thereby obtaining the maximum ballast resistance, that is to say, resistance to movement of the ties in the ballast. This, of course, very materially decreases,—in fact substantially eliminates,—rail creeping.

45 Briefly, my improved anchor comprises a U-shaped member, the legs of which are bent at an angle to the body portion thereof and provided with cutting faces extending parallel to the body portion of the anchor. I have found in practice that by pro-

viding these improved cutting faces checking or splitting of the ties when the anchor is applied thereto is effectually prevented.

In the accompanying drawings I have illustrated an embodiment of my invention.—

Fig. 1 showing my improved anchor in perspective and

Fig. 2 showing a section of a railroad track with several of my improved anchors applied thereto.

Referring to the drawings in detail and first of all to Fig. 1,—it will be seen that my improved anchor comprises a body portion A and legs B—B, these legs being bent 70 at an angle to the body portion so that the anchor as viewed in Fig. 1 may be said to be substantially U-shaped. The legs B—B are each provided with beveled faces C which form a cutting edge and as will be 75 seen from Fig. 1 are substantially parallel to the body portion A.

It will be understood, of course, that each leg B may be provided with one or two beveled faces C as desired.

80 In Fig. 2 D indicates rails which are spiked to ties E in the usual manner, the ties resting in the ballast F of the road bed. At G there is a joint in the rails and one of my anchors 4 has been driven into a tie 85 at each side of this joint.

As will be seen from Fig. 2, the anchor is preferably also applied to other ties along the track and it is to be understood, of course, that the anchor may be made of any 90 convenient length so as to span more than two ties if desired.

95 As above pointed out the beveled faces C are parallel or substantially parallel to the body portion A of the rail anchor so that when the rail anchor is driven into the ties checking or splitting of the ties is prevented.

From the foregoing it will be seen that I have provided an improved rail anchor 100 adapted to be applied to two or more ties of a track to which the rails are secured, whereby the ties to which the rail anchor is applied will be rigidly secured to each other to offer an increased resistance to movement of the ties in the ballast of the road bed to thereby eliminate or substantially 105 eliminate creeping of the rails.

While I have described a specific embodiment of my invention it is to be understood 110

that changes may be made therein without departing from the spirit and scope of my invention;—for example, the rail anchor illustrated is substantially square in cross section whereas, as a matter of fact, it could just as well be round or half round for example. Likewise, the legs B have been shown bent at substantially right angles to the body portion A whereas it comes within 10 the scope of my invention to vary this angle as desired.

What is claimed as new is:

A rail anchor comprising a body portion,

a log at each end thereof, said body portion being elongated with respect to said legs 15 to enable the anchor to span a pair of ties and the legs of the anchor to be simultaneously driven into said ties, each leg being beveled to produce a cutting edge parallel with the body portion and crosswise of the 20 grain of the ties into which the anchor is driven.

This specification signed this 19th day of July, 1921.

JOHN A. BODKIN.
